UNITED STATES PATENT OFFICE.

CHARLES FRANCIS JENKINS, OF WASHINGTON, DISTRICT OF COLUMBIA.

WHEEL-RIM.

1,032,286.

Specification of Letters Patent.

Patented July 9, 1912.

Application filed July 28, 1911. Serial No. 641,084.

To all whom it may concern:

Be it known that I, CHARLES FRANCIS JENKINS, a citizen of the United States, residing at Washington, in the District of Columbia, have invented certain new and useful Improvements in Wheel-Rims, of which the following is a specification, reference being had therein to the accompanying drawings.

10 The present invention relates to vehicle wheels and more especially to the rims of the same.

The leading object is to provide for heavy vehicles, light, durable and readily repaired 15 demountable rims having non-slipping tread surfaces, but certain features of the invention may be used with permanently attached rims.

In the accompanying drawings, Figure 20 1 shows a portion of a wheel in side elevation. Fig. 2 is a section on the line 2—2, Fig. 1. Fig. 3 is a plan view of the rim.

In these figures, A represents the felly of 25 a wheel and B a heavy metal band having a conical peripheral or tread surface, upon which a demountable rim is secured. The rim carries, instead of an ordinary tire, wood blocks C closely fitted together to form a 30 ring, and each having the grain of the wood radial with respect to the wheel. The tread face of this ring is provided with a central groove in which lies a resilient sinuous band or tire-like bar D of steel, the deflections being very numerous and alternately 35 to the right and left with respect to the medial plane of the wheel. Near the inner side of this ring the wood projects outward on each lateral face to form slightly projecting annular ribs C', C''. The wood ring 40 is held in or between two annular steel rim members F, F', which fit its lateral and inner surfaces, and extend nearly to the medial line of the latter. Through the outer plane portions of these members and the 45 intervening wood ring bolts G are passed at suitable intervals, binding the parts together. This structure is secured to the coned wheel by means of pairs of broad oppositely turned wedges H, H' drawn toward 50 each other by bolts I and each preferably provided with an upwardly extend-

ing portion H² curved like the adjacent portion of the members F, F' and at a very short distance therefrom when the wedges are pressed home. The wood ring may be 55 called a tire body, for convenience in distinguishing different parts of the whole structure, although it obviously is in some respects more like a felly.

The method of attaching and detaching 60 the rim requires no explanation. The end-grain wood of the wearing surface is well adapted to resist wear, and the wood being thoroughly impregnated with suitable water excluding and decay resisting material the 65 whole is durable. The wood lessens noise, is slightly elastic, and does not transmit shocks and vibrations like metal. The wavy bar D retards wear upon the wood and its zig-zag course causes it to prevent slipping 70 of the wheel much as do the diagonal ribs sometimes found on the tread surfaces of wheels. Obviously the rim may be replaced at any time without removing other parts. So if any block fails sooner than the rest, it 75 may be readily replaced if the member F', for example, be first detached. The steel bar D further serves as an extremely strong spring extending slightly if the wood swells and by its resistance still binding the blocks 80 firmly together if the wood shrinks.

What I claim is:—

1. The combination with a wheel provided with closely contiguous wood blocks forming a peripheral ring, of an annular, sinuous, spring metal band encircling said ring and yieldingly pressing said blocks toward the center of the wheel. 85

2. A demountable wheel rim bearing an annular tire body, or tread member, of 90 wood circumferentially grooved and made up of blocks pressed inwardly with approximately constant force by an annular sinuous band of spring metal lying in the groove. 95

In testimony whereof I affix my signature in presence of two witnesses.

CHARLES FRANCIS JENKINS.
